US0D1009215S

(12) **United States Design Patent** (10) **Patent No.:** **US D1,009,215 S**
(45) **Date of Patent:** **** Dec. 26, 2023**

(54) **DISTILLER**

(71) Applicant: **Hangzhou HooLoo Industrial Co., Ltd.**, Zhejiang (CN)

(72) Inventor: **Haining Xu**, Zhejiang (CN)

(73) Assignee: **Hangzhou HooLoo Industrial Co., Ltd.**, Zhejiang (CN)

(**) Term: **15 Years**

(21) Appl. No.: **29/853,218**

(22) Filed: **Sep. 14, 2022**

(51) LOC (14) Cl. **23-01**

(52) U.S. Cl.

USPC **D23/207**

(58) **Field of Classification Search**

USPC D23/205-207

CPC B01D 3/00; B01D 3/02; B01D 3/42

See application file for complete search history.

(57) **CLAIM**

The ornamental design for a distiller, as shown and described.

DESCRIPTION

FIG. 1 is a front, right and top perspective view of a distiller, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged detail view of portion 9 encircled in FIG. 1.

The broken lines shown in the drawings are included for the purpose of illustrating portions of the distiller that form no part of the claimed design.

1 Claim, 9 Drawing Sheets
